CLAIM

The ornamental design for a combination ceiling fan blade and iron, as shown and described.

DESCRIPTION

FIG. 1 is a perspective view of a combination ceiling fan blade and iron in accordance with my design;

FIG. 2 is a bottom plan view of the combination ceiling fan blade and iron shown in FIG. 1, but in a detached position;

FIG. 3 is a top plan view thereof;

FIG. 4 is a left-side elevation view thereof;

FIG. 5 is a right-side elevation view thereof;

FIG. 6 is a front elevation view thereof; and,

FIG. 7 is a rear elevation view thereof.

The broken-line disclosure of elements is understood to represent portions of the article in which the design is embodied, but which form no part of the claimed design.

1 Claim, 2 Drawing Sheets
